UNITED STATES PATENT OFFICE.

HARRY COBURN TURNER, OF LOS ANGELES, CALIFORNIA.

SPRING-RECOIL GRIP.

1,232,443.

Specification of Letters Patent.

Patented July 3, 1917.

Application filed February 1, 1915. Serial No. 5,373.

To all whom it may concern:

Be it known that I, HARRY C. TURNER, a citizen of the United States, residing at Los Angeles, in the county of Los Angeles and State of California, have invented certain new and useful Improvements in Spring-Recoil Grips, of which the following is a specification.

This invention relates to improvements in 10 spring recoil gripping mechanism, and has particular relation to means adapted to be applied to the leaves of springs whereby friction between said leaves will be produced upon the rebound of the spring and 15 whereby the said rebound or recoil is checked or retarded and all throw usually due thereto, absorbed and prevented.

It is an object of the invention to provide 20 means adapted to grip the leaves of a spring so as to increase their friction when moving in one direction, the said gripping action being relieved when the leaves of the spring are moving in the other direction.

It is also an object of the invention to provide 25 a spring recoil grip device which may be applied to leaf springs in such a manner that when the springs are straightened out under the action of a load, the leaves of the springs will be free to move upon each other, but when the said springs are in the act of 30 rebounding, the said leaves will be caused to rub tightly against each other for relieving throw due to recoil.

With these and other objects in view, the 35 invention comprises certain novel constructions, combinations and arrangements of parts as will be hereinafter fully described and claimed.

In the accompanying drawing:

40 Fig. 1 is a side elevation of a three-quarter elliptic spring applied to a vehicle, and having the improved spring recoil grip mechanism mounted thereon.

Fig. 2 is an enlarged detail side elevation 45 of a portion of the said spring, showing one of the spring recoil grips thereon.

Fig. 3 is a detail transverse sectional view taken upon the line 3—3 of Fig. 2.

Fig. 4 is a fragmentary detail sectional 50 view taken longitudinally through superposed spring leaves, the lower portion of one of the recoil grips being shown together with the clip or eye which holds it in place.

Fig. 5 is a top plan view of one of the 55 spring recoil grips, removed from the spring.

Fig. 6 is a fragmentary detail sectional view through a portion of a spring and through a recoil grip mounted thereon, a modified form of attaching means, for said grip, being shown.

The spring recoil grip mechanism forming the subject matter of the present invention is designed to afford a simple and very inexpensive gripping device which may be 60 readily applied to a spring so as to cause the parts of the spring to rub upon each other with considerable friction, during rebound movements, thus preventing excessive rebound or recoil action in the spring. 70 While the principle of the invention may be applied to springs of various kinds it is especially applicable to leaf springs of the elliptic kind, and the invention has been illustrated in the accompanying drawing 75 in connection with a three-quarter elliptic spring, and the features and details of the invention will now be more fully described reference being had thereto.

In the said drawing, 5 indicates the upper 80 quarter elliptic member of a spring and 6 the lower semi-elliptic member thereof, the outer ends of said spring members being pivotally connected by suitable links 7. The inner end of the member 5 is shown as 85 secured by a bracket 8 to the frame of a vehicle 9. The inner end of the member 6 is pivotally connected with said frame at 10.

The spring recoil grip device is adapted 90 for use on either the upper or lower member of the spring, the action being the same in each instance, though the position of the grips on the upper member are usually inverted with respect to the position of those on the lower member.

95 Each of the spring recoil grips is made up of a shoe or movable gripping plate 11 usually formed with a transverse pivot bearing 12 extending across the central portion thereof. The inner face of the said shoe 100 is usually recessed at 13 so as to receive a friction piece or strip 14. The said friction piece 14 may be made of fiber, automobile brake lining or any other friction material which will prevent the shoe from slipping 105 easily, when the parts are under a gripping strain. The said shoe or gripping plate 11 is carried by a pivot bolt 15 which passes through the bearing 12 and at its ends passes through apertures in the ends of links 16 110 and 17. The said shoe 11 is preferably made a little wider than the leaves of the

spring so that when the pivot bolt 15 is drawn up snugly by means of its nut 18, the said links 16 and 17 will not bear against the edges of said leaves. The other ends of links 16 and 17 are apertured to engage a pivot bolt 19 which extends through an eye 20 formed upon a clip or small plate 21 which is secured to the outer leaf of the spring. Said clip 21 is usually fastened to the said outer leaf by riveting as at 22 or in any other desired manner, so that it cannot slip upon the spring leaf. The eye 20 of the said clip 21 is also usually made a little wider than the leaf of the spring to prevent the links 16 and 17 from engaging them.

The links 16 and 17 preferably extend in a slightly inclined relation to the planes of the spring leaves as clearly shown in the drawing, the arrangement being such that when the leaves carrying the clips 21 coil or bow, the gripping plate or shoe 11 will be pulled tightly against the leaf adjacent to it, the leaves of the spring between said shoe 11 and clip 21 being thus crowded tightly together, thus producing friction between the long faces of the said leaves as they move upon each other, and retarding or checking the rebound of the spring.

In order to insure the shoes 11 being in readiness at all times, for gripping the spring leaves, a spring is provided for each gripping device having a transverse portion 23 extending across the spring leaf to which the grip 21 is attached, and provided with coiled portions at the sides as at 24, from which the ends 25 of the said springs extend one upon the outer face of each of the links 16 and 17. Bent portions 26 are also provided upon the end portions 25 which are adapted to project into and engage apertures 27 and 28 formed in the links 16 and 17. The coiled portions 24 of each spring extend around and have a bearing upon the head of the bolt 19 and the nut 30 applied to the other end thereof. The transverse portion 23 bears upon the outer surface of the spring leaf which carries the device, and the ends of the spring 25 will thus tend to move the links 16 and 17 toward the tapered portion of the spring, whenever the leaves thereof are straightened out under the action of a load, and thus carry the brake shoe to a position where it will be ready to grip the spring leaves upon their rebound.

In applying the grip mechanism to an elliptic or a partially elliptic spring, or to a spring of any other desired curvature, the grips are usually secured to the leaves of the spring near the ends thereof, where the sliding movement between adjacent leaves is greatest, so as to have the greatest movement retarding or braking action upon the rebound of the spring. The resiliency of

the spring as it straightens under a load, is not interfered with in any way for as, the clip 21 advances toward the free end of the spring the shoe 11 is correspondingly advanced under the action of the spring ends 25, relieving the gripping action of the parts, but the recoil is retarded and modified to prevent excessive rebound, as the movement of the parts in a return direction causes the gripping action again. The device is especially useful when applied to vehicle springs, and particularly to the springs of automobiles or motor driven vehicles.

While the spring recoil grip may be applied to the ends of successive spring leaves, as shown in Fig. 1, it will be understood that a less number of grips may be applied if desired without departing in the least from the spirit of the invention, and for the purposes of employing a less amount of friction.

Various means for attaching the grip to the end portions of the spring leaves may be employed within the spirit and scope of the invention. Thus as shown in Fig. 6 of the drawing the end of the spring leaf may be curled to form an attaching eye 29 for receiving the bolt 19 and holding the grip device in proper position to secure the desired action therein.

It will be evident also that other minor details of construction may be altered if desired within the scope of the present invention. The arrangements should however be such that as the leaves of the spring straighten under the weight of a load, the bolts 19 with the ends of the links carried thereby will be moved outwardly along the spring, the arms 25, moving the said links also in correspondence therewith so as to cause the shoes 11 to take up any slack in the parts and thus always be ready to crowd the spring leaves tightly together upon the recoil thereof.

While it is usually preferable to employ the grip for checking the rebound of a spring, it will be understood that the device can be used to control or affect the movement of the spring in the opposite direction, or when yielding under a load. In this instance it is only necessary to reverse the position of the coil spring, whereby the friction shoe 11 will be moved to grip the leaves when the spring is yielding under compression, all within the spirit and scope of this invention.

What is claimed is:

1. A recoil grip device, for springs having a plurality of leaves, adapted to be drawn tightly about said leaves by the longitudinal movement of the leaves with respect to each other for crowding them together upon movement.

2. A spring recoil grip comprising a fric-

130

tion member and means for moving each member longitudinally of the spring for causing the friction member to grip the parts of the spring and increase their friction engagement with each other.

3. A spring recoil grip for leaf springs comprising a leaf engaging friction member, means connected with one of the leaves of the spring for causing said friction member to crowd the spring leaves together and means for throwing the friction member into gripping position.

4. A spring recoil grip adapted to embrace a plurality of the leaves of a spring and adapted to movably engage the face of a leaf on one side of the spring, means for connecting the grip with a leaf on the other side of a spring whereby the parts may be caused to crowd the leaves together to retard their recoil action and spring means for moving the grip into gripping position.

5. A spring recoil grip having a shoe adapted to engage, with a movable frictional engagement one leaf of a spring, means for pivotally connecting the grip with another leaf of the said spring and a spring for automatically taking up any slack in the movement of the grip, whereby the parts will always be in readiness to grip the spring and retard its recoil.

6. A spring recoil grip comprising a friction shoe adapted to press against one leaf of a spring, an attaching clip secured to another leaf of the spring, connecting links extending from said shoe to said clip and spring means for holding the links in such relation to the leaves of the spring as to crowd them together during rebound movements of the spring and thus check the recoil.

7. A spring recoil grip comprising a spring engaging shoe, links pivotally connected therewith, means for pivotally connecting the links with the spring to be gripped, a spring connected with the gripping device and having a bearing against the spring to be gripped whereby the gripping device is automatically kept in gripping position.

8. A spring recoil grip comprising an attaching clip carried by the leaf of a spring to be gripped, a pivot bolt carried thereby, links pivotally held by said bolt

and adapted to embrace the leaves of a spring between them, a shoe pivotally held between the swinging ends of said links and having friction means adapted to engage and press upon an adjacent leaf of the spring to be gripped, a grip actuating spring having bearings upon the said pivot bolt and having a transverse portion engaging the spring to be gripped, said actuating spring also having end portions connected with the said links whereby the said links will normally keep the said shoe in spring engaging position.

9. A mechanical means pivoted at one end to a spring and having at the other end a friction gripping member for increasing and controlling the friction between the leaves of the spring.

10. A spring grip device having a swinging clip, a gripping member carried thereby and means for swinging the clip to keep said member in a gripping position.

11. A spring grip device comprising a swinging clip, a gripping member carried by the free end thereof and spring means for swinging the clip to keep said member in gripping position.

12. A spring gripping device comprising a swinging clip normally extending obliquely across the edges of the leaves of a spring and a frictional member tending to prevent the clip from pulling into a position straight across the leaves, whereby the movement of the spring leaves is retarded.

13. A recoil grip device comprising a pivoted clip, a gripping shoe carried thereby and means for moving said clip on its pivot to keep said shoe in gripping position.

14. A one way spring gripping device, pivotally connected with one leaf of a spring and having a grip member engaging another leaf, the structure being such that the spring is free to bend in one direction but is restrained against bending in the other direction.

In testimony whereof, I have hereunto set my hand, in presence of two witnesses.

HARRY COBURN TURNER.
